UNITED STATES PATENT OFFICE.

GORDON F. GILLESPIE, OF LOS ANGELES, CALIFORNIA.

DESIGN FOR A DOLL.

55,511.

Specification for Design.

Patented June 22, 1920.

Application filed March 31, 1919. Serial No. 286,574. Term of patent 14 years.

To all whom it may concern:

Be it known that I, GORDON F. GILLESPIE, a citizen of the United States, residing at Los Angeles, in the county of Los Angeles and State of California, have invented a new, original, and ornamental Design for Dolls, of which the following is a specification, reference being had to the accompanying drawing, forming part thereof.

In the drawing,

I claim:

The ornamental design for a doll as shown.

GORDON F. GILLESPIE.
